UNITED STATES PATENT OFFICE

150,506

DESIGN FOR A MEMORANDUM HOLDER
UNIT

William Le Blanc, Fort Worth, Tex.

Application August 26, 1946, Serial No. 132,846

Term of patent 3½ years

(Cl. D74—5)

To all whom it may concern:

Be it known that I, William Le Blanc, a citizen of the United States, residing in Fort Worth, in the county of Tarrant and State of Texas, have invented a new, original, and ornamental Design for a Memorandum Holder Unit, of which the following is a specification, reference being had to the accompanying drawing, forming part thereof.

I claim:

The ornamental design for a memorandum holder unit, substantially as shown.

WILLIAM LE BLANC.
